CUFF BUTTON

Filed Feb. 18, 1932

UNITED STATES PATENT OFFICE

ALPHA H. METCALF, OF ATTLEBORO, MASSACHUSETTS, ASSIGNOR TO THE BAER & WILDE COMPANY, OF ATTLEBORO, MASSACHUSETTS

CUFF BUTTON

Application filed February 18, 1932. Serial No. 593,761.

This invention relates to cuff buttons, and the primary object thereof is to provide a cuff button which has novel means for mounting the ends or heads thereof so that same may be moved into the plane or shank of the body of the button in positioning same, and subsequently moved to extend at substantially right angles to said shank so as to retain the button in position on the garment.

10 A further object of the invention is to provide heads which may be moved to lie on opposite sides of the shank and to further provide a simplified and economical construction involving a minimum of parts

15 which are secured without the use of solder and wherein the heads can be easily and quickly turned to their different positions and wherein same are effectively held in all of such positions.

20 In the drawing:

Figure 1 is a plan view of the invention;

Figure 2 is a section on line 2—2 of Figure 1, showing the heads turned at right angles in dotted position:

25 Figure 3 is a section on line 3—3 of Figure 1;

Figure 4 is a detail view of the free ends of one of the heads, and

30 Figure 5 is a section on line 5—5 of Figure 4.

In proceeding in accordance with the present invention a shank 1 is employed which may be of any ornamental form desired and as here shown is formed with cups 2 at its ends in which jewels or other ornamental gems or the like may be secured. The shank or body 1 is formed with an axial or longitudinal bore in which a rod 4 is disposed. The bore 4 is bisected by transverse openings 5 in which the ends 5 of the head 6 are journaled. As shown in Figures 4 and 5 the ends 5 of the heads are formed with cruciformed grooves 7 which grooves are of a size to have snapping engagement with the end portions of the rod 4. The rod 4 is held against axial movement by the gems at the end portions of the shank 1, although it will be understood that the gems can be omitted and the rod 4 held against axial displacement by other means.

From the foregoing it will be seen that the ends 5 with their cruci-form groove 7 of each head are disposed on opposite sides of the end portions of the rod 4, consequently the latter forms a common means for latching each of the ends 5 of each of the heads 6, thereby affording a most economical, simple and compact structure, involving a minimum of parts.

Since the heads are preferably formed of wire or other material having spring properties, it will be seen that the ends 5 thereof can be readily sprung into and out of engagement with the rod, and at the same time are effectively held in latched position.

Having thus described my invention what I claim as new and desire to secure by Letters Patent is.

1. In a button, a shank having a longitudinal bore and spaced transverse openings bisecting the bore, a rod in the bore extending across the openings, and heads each having spaced ends which are journaled in the openings and lie on opposite sides of the rod and have cruci-form grooves which are formed to snap into engagement with the rod thereby to latch the heads in different positions.

2. In a button, a shank having a longitudinal bore and spaced transverse openings bisecting the bore, a rod in the bore extending across the openings, and heads each having spaced ends which are journaled in the openings and lie on opposite sides of the rod and have grooves to snap into engagement with the rod thereby to latch the heads in position.

3. In a button, a body having spaced transverse openings, heads each having spaced ends journaled in the openings, and means in the body common to each of the heads to engage the ends of the heads to latch the heads in position.

4. In a button, a body having spaced transverse openings, heads each having spaced ends journaled in the openings, and means independent of and disposed in the body to engage the ends of the heads thereby to latch the latter in position.

5. In a button, a body, spaced heads having spaced ends journaled in the body, and

means independent of and carried by the body and common to each of the heads to latch same in different positions.

6. In a button, a body, spaced heads having spaced ends journaled in the body and formed with grooves on their end faces, and means in the body common to each of the head ends and engageable with the grooves to latch the heads in position.

10 7. In a button, a body, spaced heads having spaced ends journaled in the body and formed with grooves on their end faces, and means independent of and disposed in the body and engageable with the grooves to latch the heads in position.

15 8. In a button, a body element, and a head element having spaced ends journaled in the body element, one of said elements having seats and the other element having means independent thereof for snapping engagement with the seats to hold the head element in different positions.

20 9. In a button, a body having a transverse opening, a head having spaced ends provided with seats, journaled in the opening, and a rod-like element in the body extending across the opening and in the space between the head ends for engagement on its opposite sides with the seats of the respective head ends.

25 10. In a button, a body having a transverse opening, a head having spaced ends journaled in the opening and one of which ends is provided with seats, and means independent of the body and carried thereby and extending into the opening for engaging in the seats to hold the head in different positions.

30 11. In a button, a body, a head having spaced ends journaled in opposite sides of the body and each provided with seats, and means in the body independent of the latter for snapping into the seats thereby to hold the head in different positions.

35 12. In a button, a body, a head having a pair of parts journaled in the opposite sides of the body, and means in the body and independent of the latter for latching one of the head parts in different positions.

In testimony whereof I have signed my name to this specification.
